USPC **D14/492**

CLAIM

(58) **Field of Classification Search**

The ornamental design for a display screen with graphical user interface, as shown and described.

USPC D14/485-495; 345/1.1, 1.2, 2.1-2.3, 3.1, 345/902; 715/763, 810, 836, 837, 846, 715/847, 977

DESCRIPTION

CPC G06F 3/048; G06F 3/0481; G06F 3/04812; G06F 3/04817; G06F 3/0482; G06F 3/0483; G06F 3/0484; G06F 3/04847; G06F 3/0485; G06F 3/04855; G06F 3/04886; G06Q 30/00; H03J 1/00; H03J 1/0008; H03J 1/0016; H03J 1/0025; H04N 5/00; H04N 5/08; H04N 5/14; H04N 5/22; H04N 5/225; H04N 5/232; H04N 5/445; H04N 5/44543; H04N 5/45; H04N 2005/44517; H04N 2005/44521; H04N 2005/44526; H04N 2005/4453; H04N 2005/44534; H04N 2005/44539;

The FIGURE is a front view of a display screen with graphical user interface.

The outermost broken line illustrates a display screen and forms no part of the claimed design. The long-dash/short-dash broken line illustrates the boundary of the design and forms no part of the claim. The remaining broken lines illustrate portions of the graphical user interface that form no part of the claimed design.
